THREAD PULL-OFF DEVICE FOR BUTTON-HOLE SEWING MACHINES

Joseph H. Pikul, Boston, Mass., assignor to The Reece Button Hole Machine Company, Boston, Mass., a corporation of Maine

Original application October 27, 1934, Serial No. 750,335. Divided and this application July 13, 1935, Serial No. 31,215

5 Claims. (Cl. 112—253)

This invention relates to sewing machines of the type adapted to sew a short seam and then come to rest and particularly to a sewing machine of this type which is constructed so that when the short seam is completed the needle comes to rest in a raised position with a loop of needle thread caught on the under thread mechanism beneath the work, and which is also constructed with means for breaking or disrupting the needle thread beneath the work at the last stitch.

An object of the invention is to provide an improved device for engaging the needle thread between the work and the needle after said thread has been broken or disrupted and pulling the broken end of the needle thread back from the work and holding it until the first stitch has been formed on the next succeeding seam.

In order to give an understanding of the invention I have illustrated in the drawings a selected embodiment thereof of which will now be described after which the novel features will be pointed out in the appended claims.

In the drawings:

Fig. 1 is a side view of a sewing machine embodying my invention.

Fig. 2 is an enlarged view showing the thread pull-off device in position ready to engage the needle thread and pull it back through the cloth.

Fig. 3 is a fragmentary top plan view of the pull-off device.

Fig. 4 is a fragmentary side view of the thread pull-off device looking at it from the opposite side from that shown in Fig. 1.

The sewing machine shown in Fig. 1 is of the usual type having the work frame 1 for supporting the work 2 in which the short seam is to be sewed, which work frame supports the work clamps 3 for clamping the work in position during the sewing of the seam, and also having the stitch frame 4 carrying stitch-forming mechanism, said stitch frame and work frame being movable relative to each other. The stitch-forming mechanism is of the usual type including a vertically-reciprocating needle 5 operating above the work and carried by a needle bar 6 which reciprocates in the head portion 7 of the stitch frame and also including under thread mechanism shown diagrammatically at 8 in Fig. 2 and 50 which is preferably in the form of loopers and looper-spreaders carried by the turret 9 which is rotatably mounted in the lower portion 10 of the stitch frame. 11 indicates the usual main cam by which the operations of the machine are controlled, said cam being rotatably mounted in the cam housing 12 forming part of the stitch frame as usual in sewing machines of this type.

In the particular embodiment herein illustrated the relative feeding movement between the stitch frame 4 and work frame 1 is secured by movement

of the stitch frame 4 forwardly and backwardly on the work frame.

Sewing machines of this type are usually constructed so that the stitch-forming mechanism comes to rest at the completion of each short seam with the needle raised as shown in Figs. 1 and 2 and with a loop 13 of needle thread 14 caught on the under thread mechanism 8 beneath the work.

These sewing machines are also usually provided with some means for disrupting or severing the needle thread beneath the work at the last stitch and one way in which this is frequently accomplished is by providing means for moving the stitch frame forwardly after the stitch-forming mechanism has come to rest, thereby to apply sufficient strain on the needle thread to cause one leg of the loop 13 to break at the last stitch, this being the construction illustrated in my co-pending application Serial No. 750,335, filed October 27, 1934 of which this application is a division.

After the needle thread 14 is thus broken it is necessary to withdraw the broken end from the work before the stitching on the next short seam begins and the present invention relates to a novel means for engaging the needle thread between the needle and the work and withdrawing the broken end of the thread from the work and holding said end until the first stitch is formed on the succeeding short seam.

This pulling of the needle thread 14 back from the work is accomplished by a pull-off member 15 which is carried by a supporting lever 16 pivotally mounted on the stitch frame at 17 and provided with a tail portion 18 adapted to be engaged by a cam hump 19 with which the main cam 11 of the machine is provided. The supporting lever 16 is similar to the usual cutter lever in a buttonhole sewing machine, and in fact, if the sewing machine 1 is of the type designed to sew a short seam in the nature of a buttonhole then the lever 16 might be the lever carrying the buttonhole cutter for cutting the buttonhole slit. This supporting lever 16 is acted upon by a spring 20 which normally holds it in its raised inoperative position shown in Fig. 1 and the cam hump 19 is so positioned that it will engage the tail 18 of the lever 16 just after the stitch-forming mechanism comes to rest, thereby swinging said lever 16 into its lowered position shown in Fig. 2, and when the cam hump 19 has passed the tail 18 the spring 20 will return the lever 16 to its raised position.

The downward movement of the lever 16 into the position shown in Fig. 2 causes the pull-off member 15 to wipe by the portion of the needle thread 14 extending from the needle to the work, and the return movement of the lever 16 to its raised position causes the thread pull-off member

to engage the thread 14 to pull the broken end thereof back through and free from the work.

The pull-off member 15 is provided at its free end with a hooked portion 21 and is also provided with a felt strip 22, the outer end of which engages the inner face of the hooked member 21. This pull-off member 15 is pivoted at 23 to one end of a lever 24 which in turn is pivoted intermediate its ends at 25 to the supporting lever 16. The other end of the lever 24 is pivotally connected at 30 to one end of a link 26, the other end of which link is pivoted to the stitch frame at 27. 28 indicates a spring acting on the pivoted pull-off member 15 and tending to resist upward swinging movement of said pull-off arm relative to the lever 24. 29 indicates a stop or rest carried by the lever 16 and against which the member 15 is yieldingly held by the spring 28. 20 When the supporting lever 16 is in its normal raised position shown in Figs. 1 and 4 the pull-off finger or member 15 will be situated in the rear of the needle as also shown in Figs. 1 and 4. When the supporting lever 16 swings clockwise 25 into its lowered position shown in Fig. 2, the short lever 24 will be turned from the position shown in Fig. 1 to that shown in Fig. 2 by the action of the link 26, and this turning movement will slide the pull-off finger 15 forwardly over the rest 29 into the position shown in Fig. 2, the spring 28 holding the pull-off finger in engagement with the rest during such movement. This movement of the pull-off finger carries the hooked end 21 past the needle thread 14 as shown 30 in Fig. 2 into a position in front thereof. The shape of the hooked portion 21 is such that during its forward movement it will readily wipe by the thread 14 without catching thereon and when the pull-off member is in its forward position it 35 will have a position relative to the thread 14 shown in Figs. 2 and 3.

As the supporting lever 16 swings back into its raised position the pull-off finger 15 will be given a backward movement into the position shown in 45 Figs. 1 and 4 and during this backward movement the needle thread 14 is caught by the hook 21 with the result that the broken end of the needle thread will be pulled free from the work 2. During the pulling of the thread 14 free from the 50 work said thread becomes caught between the felt strip 22 and the inner face of the hook 21 and said felt provides sufficient frictional engagement with the thread to hold the end as shown in Figs. 1 and 4. The end of the needle thread will 55 thus be held until the first stitch is formed on the next seam and as soon as this has been accomplished the strain on the thread will pull it free from the pull-off arm.

1. A sewing machine having work-holding means, stitch-forming mechanism including a needle, said stitch-forming mechanism and work-holding means having a backward and forward relative movement, a pivotally-mounted lever, means to give said lever an oscillating motion at 60 the end of a sewing operation, a thread pull-off member carried by said lever and having a thread-engaging portion normally situated in the rear of the needle, means operative during the swinging movement of said lever in one direction to move 65 the pull-off member relative to said lever forwardly in the direction of said relative movement thereby to carry its thread-engaging portion into

a position in front of the needle and operative during the movement of said lever in the opposite direction to move the pull-off member backwardly thereby causing the thread-engaging portion thereof to engage the needle thread and pull it 5 free from the work.

2. A sewing machine having work-holding means, stitch-forming mechanism including a needle, said stitch-forming mechanism and work-holding means having a backward and forward 10 relative movement, a rocking lever situated above the work and movable toward and from the latter, a thread pull-off member mounted on said lever and adapted to move relative thereto in the direction of said relative movement, means to give 15 the lever a movement toward the work and then away from the work at the end of a sewing operation and means connected with said pull-off member to give it a backward movement to engage the thread leading from the needle to the 20 work and pull said thread free from the work during the return movement of said lever.

3. A sewing machine having work-holding means, a stitch frame, stitch-forming mechanism including a needle mounted on said stitch frame, said stitch frame and work-holding means having a backward and forward relative movement, a lever pivoted to the stitch frame, means to give the lever a movement toward the work and then a reverse movement at the end of the 25 sewing operation, a thread pull-off finger mounted on said lever and adapted to move relative thereto in a forward and backward direction, said finger being normally situated in the rear of the needle, and means to move the thread pull-off finger 30 forwardly during the movement of the lever toward the work and rearwardly during the reverse movement of the lever thereby to cause said pull-off finger to engage the thread between the needle and work and pull it back from the work. 35

4. A sewing machine having work-holding means, stitch-forming mechanism, a pivotally-mounted lever, means operative at the end of the sewing to give the lever a movement toward the work and then a reverse movement, a rocker pivotally mounted on said lever, a pull-off finger pivotally connected to one end of said rocker, and means connecting the other end of said rocker to a fixed support, whereby when the lever moves toward the work the pull-off finger is moved forwardly into position to engage the thread and when the lever has its reverse movement the thread pull-off finger pulls the thread back from the work. 45

5. A sewing machine having work-holding means, stitch-forming mechanism including a needle, a pivotally-mounted lever, means to give said lever an oscillating motion at the end of a sewing operation, a thread pull-off finger pivotally mounted on said lever to turn about a horizontal axis, means connecting said pull-off finger to a fixed support, said finger having a position in the rear of the needle when said lever is in raised position, said connection operating to swing the pull-off finger forwardly relative to the lever as the latter moves toward the work to move the thread-engaging portion of said finger into a position in front of the needle and to swing said pull-off finger backwardly as the lever is raised, thereby to cause said finger to engage the thread 60 and pull it free from the work. 65

JOSEPH H. PIKUL
